2,080,588

CRANKCASE VENTILATOR FOR INTERNAL COMBUSTION ENGINES

Ralph S. Whittington, Oak Park, Ill., assignor to Bendix Products Corporation, South Bend, Ind., a corporation of Indiana

Application June 17, 1932, Serial No. 617,827
Renewed October 24, 1936

9 Claims. (Cl. 123—171)

This invention relates to the ventilation of the crankcase of an internal combustion engine. One of the primary objects of this invention is to provide means of reducing the crankcase dilution or the percentage of gasoline which is normally mixed with the lubricant in the crankcase. The further object of this invention is to reduce the oil consumption and leaks which normally take place in the crankcase of an internal combustion engine.

Figure 1 is the semi-diagrammatic view partly in section of a crankcase ventilating system. Figure 2 is a fragmentary sectional view illustrating an optional control means for this ventilating system.

The common practice has been to circulate air through the crankcase by providing an inlet and outlet at such points that a difference in atmospheric pressure would exist between them when the car was being driven. The method illustrated in Figure 1 has a number of important advantages over prior methods. It is so arranged that any degree of vacuum up to full intake manifold vacuum can be maintained in the crankcase when the motor is designed for this system. Since the vacuum in the crankcase is adjustable it can be made to move varying quantities of air through the crankcase by controlling the size of the openings and leakage into the crankcase. Also, the path that air travels through the crankcase may be controlled by the location of the suction connection and inlet points. Other advantages are positive removal of fumes from the crankcase by drawing them into the intake manifold; greater reduction of crankcase dilution due to the fact that more gasoline will boil off at a given temperature when the air pressure is reduced; reduction of oil consumption by creating a lower than atmospheric pressure on the crankcase side of the pistons and also by eliminating the loss of oil through the conventional crankcase ventilator and by preventing oil leaks from the crankcase due to atmospheric pressure on the outside; reduction of motor noises by closing large openings in the crankcase.

This invention also contemplates the use of a control valve which will entirely cut out the ventilating system at low motor speeds in order that the gas coming from the crankcase will not disturb the carburetion of the motor.

Referring then particularly to the drawing, there is shown in Figure 1 a system which is comprised of a passage 1 which may be any section of the intake manifold, but preferably the carburetor riser near the intake manifold. Into

passage 1 is tapped a conduit 21 which at its other end is tapped into the crankcase 10. Conduit 21 is provided with lateral extensions 22 and 23 and these extensions contain a bore 24 which slideably receive a valve 4 arranged to divide the conduit 21 into passage 2 and passage 8. Valve 4 is actuated at one end by spring 9 and at the other end by diaphragm 6 enclosed in casing 25. The passage 8 is provided with jet 13 which is connected to conduit 14, conduit 14 being intended for connection to the carburetor bowl to supply gasoline. Crankcase 10 is provided with a series of holes as 12 to regulate the location and capacity of air inlets.

In the operation of the system conduit 21 is directly connected to passage 1 and is subject to the vacuum in the intake system. As soon as the motor is started the vacuum will act through passage 2 through undercut 3 in valve 4, through passage 5 formed by the bore of extension 23 and a flat side of valve 4 and on diaphragm 6. The effect of this vacuum is to allow atmospheric pressure acting through hole 7 to move diaphragm 6 and valve 4 to shut off passage 2 from passage 8, but adjustable spring 9 tends to hold valve 4 to open passage 2 to passage 8. The result is that valve 4 opens passage 2 to passage 8 just enough to allow sufficient vacuum to be applied through passage 5 to diaphragm 6 to produce a force equal to the force of spring 9 just at the point valve 4 is about to close passage 2 from passage 8. Hole 15 is provided to insure the free movement of piston 4. Therefore the vacuum in passage 8 is determined by the strength of spring 9 and the area of diaphragm 6. Since spring 9 is adjustable it can be adjusted to permit the production of any vacuum in passage 8 from full manifold vacuum (if the crankcase is tight) to no vacuum at all. Passage 8 passes to crankcase 10 through port 11 for the creation of a partial vacuum in the crankcase. This will cause a flow of air and fumes from the crankcase into the intake system, and the rate of this flow will depend upon the size of passage 2 and passage 8, the vacuum created in the crankcase and the nature of leakage and air inlets to the crankcase. Optional holes, as hole 12, may be provided to control the quantity and path of air through the crankcase.

Optional jet 13 may be used in cases where large quantities of air are moved through the crankcase to mix this air with gasoline. Conduit 14 leads to the carburetor bowl and delivers gasoline through jet 13 in proportion to the vacuum in passage 8 and the velocity of air flowing in

passage 8. This jet may be provided with an adjustment at 13 but preferably at the carburetor bowl. This jet is located between valve 4 and the crankcase so that its delivery of gasoline will be sensitive to the vacuum in the crankcase.

In Figure 2, 2-a represents a portion of the passage 2 in Figure 1. Vacuum in passage 2-a acts through passage 20 formed by a flat side on the valve 16 and the inner periphery of the threaded extension carried by the conduit and on diaphragm 17 to close valve 16 and shut off vacuum from the crankcase entirely. But this action is opposed by spring 18 which holds valve 16 open at all times, except when the throttle valve of the carburetor is nearly closed. Then the vacuum in passage 2-a becomes great enough to allow atmospheric pressure acting through hole 18 to overcome spring 18 and close valve 16. It is obvious that spring 18 can be made of such strength as to provide for the shutting off of this vacuum from the intake manifold at any desired setting of the carburetor throttle valve.

What I claim as my invention is:

- 25 1. The combination with the fuel intake system and the crankcase of an internal combustion engine of a conduit connecting said intake system to said crankcase of said engine, a valve in said conduit between said intake system and said crankcase, an adjustable spring actuating said valve to open said conduit from said intake system to said crankcase, a diaphragm connected to said valve, a passage from the conduit to the inner face of the diaphragm whereby the vacuum in said system tends to close said conduit from said crankcase, and means for adjusting said spring to act to open said intake system to said crankcase.
- 30 2. The combination with a fuel intake system and the crank case of an internal combustion engine, of means for creating a vacuum in said crank case, said means comprising a conduit connecting the fuel intake system and the crank case, a valve extending transversely of said conduit, said valve being urged towards open position by spring means, a diaphragm carried by the valve in opposed relation to the spring means, and means whereby vacuum created in the conduit will cooperate with said diaphragm and urge the valve towards closed position against the action of the first mentioned spring means.
- 35 3. The combination with a conduit connecting the fuel intake system and the crank case of an internal combustion engine, of means for controlling the creation of a vacuum in said crank case, said means comprising a valve movable

transversely in said conduit and partially open, spring means for urging said valve towards open position, a diaphragm carried by said valve in opposed relation to the spring means and means for admitting vacuum from the conduit to one side of the diaphragm for assisting the same in urging the valve towards closed position against the first mentioned spring means.

4. The combination with the fuel intake system and the crank case of an internal combustion engine, of means for maintaining a vacuum in said crank casing, said means comprising a conduit connecting said fuel intake system and crank case, a slide valve extending transversely across said conduit, spring means cooperating with the valve on one side of the conduit and urging the same towards closed position, a diaphragm disposed on the opposite side of the conduit and to which the valve is connected and means whereby vacuum created within the conduit will be admitted to the inner side of the diaphragm thereby assisting said diaphragm in overcoming the action of the spring means at the opposite side of the conduit and in moving the valve towards closed position.

5. A device as set forth in claim 4 including a casing for the diaphragm and carried by the conduit and a passage of communication from the conduit to said casing to the inner side of the diaphragm.

6. The method of maintaining and controlling sub-atmospheric pressure in an engine crankcase comprising connecting the crankcase to a source of sub-atmospheric pressure and controlling the evacuation thru such connection in accordance with the pressure condition in the crankcase.

7. In combination an internal combustion engine including a substantially closed crankcase, a passage from said crankcase to a source of sub-atmospheric pressure and means responsive to the pressure in said crankcase for controlling the evacuation thru said passage.

8. The combination with the fuel intake system and the crankcase of an internal combustion engine, of a passage between said crankcase and said intake system, a valve means in said passage, resilient means operating to open said valve means, means responsive to the pressure in said passage between said valve and crank case and operative to close said valve means.

9. A device as set forth in claim 7 including a valve means operated at a predetermined manifold vacuum to close said conduit.
